UNITED STATES PATENT OFFICE.

ANDREW V. GROUPE, OF PHILADELPHIA, PENNSYLVANIA, ASSIGNOR TO
JOHN MURPHY, OF SAME PLACE.

CUFF-BUTTONER.

SPECIFICATION forming part of Letters Patent No. 601,137, dated March 22, 1898.

Application filed April 29, 1897. Serial No. 634,341. (No model.)

To all whom it may concern:

Be it known that I, ANDREW V. GROUPE, a citizen of the United States, residing in the city and county of Philadelphia and State of Pennsylvania, have invented certain new and useful Improvements in Cuff-Buttoners, of which the following is a full, clear, and exact description, reference being had to the accompanying drawings, forming a part of this specification.

The object of this invention is to provide a device of simple and efficient construction whereby one of the members of a link button may be readily passed through the buttonholes of a cuff, as will hereinafter appear.

In the drawings, Figure 1 is a plan of the blank from which the device is formed. Figs. 2 and 3 are face and back views, respectively, of the buttoner. Fig. 4 is an edge view thereof, showing in dotted lines the position of the cuff-button. Fig. 5 is a rear end view of the buttoner enlarged.

The cuff-buttoner in its preferred construction is struck up from a single piece of metal to form a tapering body 1, with inwardly-turned tapering edges or flanges 2, an elongated longitudinal recess or depression 3, and a slot or socket 4 at the base of the recess. The slot or socket is formed at the basal or wider end of the body, and the recess is tapered therefrom toward the point of the device, so as to form on the back of the body a longitudinally-tapering rib. The flanges are turned or bent upon the inner side of the body in a manner to diverge rearwardly from the point of the latter, the wider ends of the

flanges terminating somewhat in advance of the slot or socket, as shown.

To use the device just described, the eye of the button member to be applied to the cuff 40 is inserted in the slot or socket of the device, as indicated in Fig. 4, so that said member will lie adjacent to the rear ends of the flanges. This member and the device are thus held between the thumb and forefinger and the point 45 of the device is pushed into the buttonholes of the cuff, the rib and the lateral flanges of the device thus gradually opening or spreading the holes to permit the entrance into the latter of the opposing end of the button, whereupon the point of the device is grasped and the device, with the engaged button member, drawn entirely through the buttonholes. This being done, the device disengages itself from the eye of the button. 55

I claim—

The herein-described cuff-buttoner embodying a tapering body portion with inwardly-turned edges or flanges, an elongated longitudinal recess or depression, and a slot 60 or socket at the base of the recess, said flanges and recess tapering toward the point of the body and the rearward ends of the flanges terminating in advance of the slot or socket.

In testimony whereof I have hereunto affixed my signature in the presence of two subscribing witnesses.

ANDREW V. GROUPE.
